UNITED STATES PATENT OFFICE

ARCHIBALD H. KINGHORN, JR., OF OAKMONT, PENNSYLVANIA

TRAFFIC CONTROLLING DEVICE

Application filed August 19, 1930. Serial No. 476,294.

This invention relates specifically to an electric switching device whereby the operator of a train or car may select the direction in which he desires to proceed. The invention is, however, also applicable to the control of motor vehicles, as will be clear from the following description.

Heretofore the common method of selecting a switch generally used by electrically driven cars consists in passing a given point with the power either on or off, depending upon the desired selection. While this operation is fairly satisfactory for electrically driven cars or locomotives, it is generally necessary to slow down at this given point to a low speed such as five miles per hour to permit its proper operation. Obviously a device of this character is not adapted to steam locomotives or motor vehicles.

It is the object of the present invention to provide an automatic switching device in which the selection is obtained in a different manner without necessitating the stopping or substantial delay of the car approaching the switch. The improved type of device is moreover adapted to steam or motor driven cars.

Detailed objects of the invention whereby a proper operation is secured will be apparent from the following description read in conjunction with the accompanying drawings, in which:

Fig. 1 is a wiring diagram showing the preferred form of device applicable to electrically propelled cars; and

Fig. 2 is a wiring diagram of a similar arrangement applicable to either electrically driven or other cars or locomotives.

In the wiring diagrams various fuses, switches and the like have been omitted for the sake of clearness and the conventional features of the device have been diagrammatically illustrated, as they are well known.

Referring first to Fig. 1, 2 indicates an overhead trolley wire extending along the main track, the portion of this wire beyond the switching point 10 being designated 2'. 4 designates the trolley wire extending over the branch track from the switch point 10. 6 indicates the trolley wire on an adjacent

track, the normal direction of the cars on the two tracks being indicated by the arrows. 8 indicates the trolley wire following a connecting track between the two main tracks. The system shown is of the single overhead wire ground return type.

The position of the switch points at 10 is controlled in any well known manner by means of the plunger 12, operative in opposite directions by power solenoids 14 and 16. 60 Inasmuch as the connections between this plunger and the switching points may be of any well known variety, the details have not been shown.

In the normal condition of the system, in the absence of any cars in the operative portions thereof, the relay 18 is continuously energized. This is effected by reason of the fact that the contact 20 is maintained closed by the attraction of the armature 21 by the relay 18, the circuit being from the line 2 through the contact 20, the armature 21, the resistances 22 and 24, the relay 18, the resistance 26, the contact 28, and the solenoid 14 to the ground. By reason of this continuous energization of the relay 18, a second armature attracted thereby maintains closed the contact 30. The resistance of the relay 18, in series with the other resistances, is sufficient to prevent the solenoid 14 from normally attracting the plunger 12. The various elements of the device are in the positions described above and as illustrated in the figure when the system is free of cars. The switch will be in the position in which it was set for the passage of the last car, its position being immaterial to the subsequent operation of the system.

If, now, a car is proceeding in the direction of the arrow along the track associated with the wire 2, contact is momentarily made by the trolley's bridging the gap between the trolley wire and contact 32 which may be of the ordinary overhead variety of contact commonly used in connection with trolleys. 95 This momentary contact energizes relay 34, which is connected between the contact member 32 and ground. Contact 36 is thus closed, energizing relay 38 which in turn closes the contact 40, which acts as a locking device 100

maintaining the current through the relay. At the same time, a motor 42, which is preferably of an induction type, is started by the closure of the circuit through its main field 43. This motor drives through suitable reduction gearing, a commutator member containing a number of segments 44, 46, 48 and 50 which are illustrated developed in the figure. That is, the distance between the two dotted 10 lines indicates 360° . The first segment extends throughout the circumference and makes continuous contact with a brush 52. The second segment 46 extends through substantially 360° , but has a small break therein 15 as indicated. At the time the commutator begins a revolution, the brush 54 contacts with the advancing end of this segment. The segments 48 and 50 are arranged as shown, the segment 50 starting adjacent the end of the 20 segment 48. At the time the revolution starts, the brushes 56 and 58 do not make contact with the segments with which they are associated. All of the segments are electrically connected with each other as indicated. It will be noted that the circuit 25 through relay 38 is completed through brush 54, segments 46 and 44, and brush 52, at the beginning of a revolution. As the end of the revolution approaches, brush 54 rides off the 30 rear trailing end of the segment 46, breaking the circuit through relay 38 and deenergizing the main field of the motor. The inertia of the parts is sufficient to permit an overrunning of the motor and commutator so 35 that the break in the segment 46 passes the brush 54, which thereafter makes contact with the advancing end of the segment. Excessive overrunning is prevented, however, due to the braking effect of the auxiliary 40 field 43' which limits the overrun to one or two revolutions amounting to just sufficient movement of the commutator to renew contact between 54 and 46. It will be clear from the above that upon each energization of the 45 relay 34 by the making of contact 32 a single revolution of the commutator takes place.

Immediately after the commutator begins to rotate, brush 56 makes contact with segment 48, thereby lighting the green lamp G. 50 If, now, during the period when this lamp is lighted, the trolley passes the contact 60, the switch will be set so that it may proceed straight ahead. This is effected in the following manner:

55 When connection is made by the trolley between the line and the contact member 60, relays 62 and 64 are energized through resistance 63 and contact 30 which is normally closed. As soon as the relay 62 is energized, 60 contacts 66 and 68 are closed so that they are not only connected to the armature but also to each other through the armature. Simultaneously relay 64 closes its contact 70 so that line voltage is applied through contact 65 70, solenoid 74, and contacts 68 and 28 to

the solenoid 14 causing it to attract the plunger 12 if it is not already within the solenoid. Movement of the plunger to the left hand position illustrated fixes the switch so that the car may proceed straight ahead. The resistances in this circuit through solenoid 14 are relatively low so that a heavy current passes, furnishing sufficient power to throw the switch. 70

It will be noted that the solenoid 74 is 75 wound on the same core as the coil of relay 64 so that the same armature is attracted by both relays. Inasmuch as the relay 74 maintains contact 70 closed, it may be said to lock itself in an energized condition. 80

It is to be noted that while the contact at 60 may have been momentary, the relays 62 and 64 remain energized up to the present time by reason of the closure of contacts 66, the line voltage being applied from 71 85 through 70, 74, 66, 61, 63 and 30. Both resistances 61 and 63 suitably limit the current. The arrangement of 61 and 63 is such that a relatively heavy current flows during the initial energization, resistance 63 only 90 being in the circuit to the relays from 60.

The making of contact 70 at the same time applies the line voltage to the pole 72 of the relay 18. Accordingly line voltage is applied to both poles of the relay so that it is de-energized and contacts 20 and 30 are opened. This relay, however, is of a slow release type, so that the opening of the contacts takes place relatively slowly. Another parallel circuit to the solenoid 14 is 95 formed through contact 70, point 72, resistances 26 and contact 28. The resistance 26 is 100 preferably adjustable and approximately the same as that of either of the solenoids 14 or 16. 105

As soon as contact 30 is broken, relay 62 is de-energized, permitting an opening of contacts 66 and 68, breaking the main circuit through the solenoid 14. However, after contact 68 is broken there is still to be broken an instant later a second circuit to the solenoid 14 through the opening of 70, this circuit being through 72, 26 and 28. Very little sparking accordingly occurs at the point 68, and the resistance 26 eliminates excessive sparking at the point 70 since the current through the solenoid is substantially cut in half. The blowout coils extinguish arcs at both of these contacts. 110 115

The switch has now been thrown into its proper position to permit the car to move straight ahead and all of the relays 18, 62, 64 and 74 as well as solenoid 14 have been de-energized. In view of this, it is obvious that 125 if a succeeding car made contact at 60 immediately after the preceding car, it would not effect any change of the switch, so that thereby there is eliminated any possibility of splitting the switch under the preceding car 130

or changing its position prior to the time when the car reaches it.

In order to clear the apparatus to permit a subsequent car to actuate it, a trolley contact 76 is located along the line 2' beyond the switch. As soon as the trolley causes connection between the line and the contact 76, the circuit is closed through contact 78, relay 80, resistance 24, relay 18, resistance 26, 10 contact 28 and solenoid 14 to ground: The relay 18 thereafter closes contacts 20 and 30, contact 20 locking the same as above described so that the parts are restored to their original positions with contacts 20 and 30 15 permanently closed. The system is thus free to be operated by a succeeding car.

The above description was based on the assumption that contact was made at 60 during the time brush 56 contacted with segment 48 and the green lamp G was lighted by reason of the fact that the car maintained full speed between 32 and 60. If, however, after passing contact 32, the car proceeded more slowly, the segment 48 would have 25 passed brush 56 and contact between segment 50 and brush 58 would have taken place. In this case, the yellow lamp Y would have been lighted and relay 82 energized, attracting its armature and closing contact 84. 30 If, then, during the period when the yellow lamp was lighted, the car closed the contact at 60, a series of operations similar to that above described would take place, with the exception that the current would pass 35 through contact 84, energizing solenoid 16, whereby the switch would be thrown so as to cause the car to turn from the main track and proceed in the direction of the wire 4. In this case, the clearance of the system 40 would be effected by the closure of the contact 86.

It will be clear from the above that the contacts 32 and 60 may be so spaced that a minimum of delay would be occasioned to a 45 car which is to take the branch track; for example, the contacts might be so spaced that a reduction to half speed would suffice to secure proper operation. If a car, intended to proceed straight ahead, should be delayed between 32 and 60, it would be necessary to 50 wait till the lamp Y was extinguished whereupon contact at 60 would set the switch for straight ahead movement.

The lamps G and Y should be adjacent 55 contact 60.

In order to warn the operator of the car of the proper position of the switch, which might be some distance beyond 60, prior to the time the car moves thereover, there is provided a relay 88 connected to the line and to the ground through the parallel green and yellow lights G₁ and Y₁, as will be now described. The energization of the relay 88 breaks the contact 90, thereby opening the 60 circuit through a red lamp R. Whenever the

relay 88 is de-energized, the contact at 90 is made, lighting the red lamp. The three lamps Y₁, G₁, and R are adjacent the switch.

In series with the yellow and green lamps Y₁ and G₁, respectively, are brushes 92 and 70 94 arranged to contact with a segment 96 as it moves from one extreme position to another. The segment 96 illustrated in Fig. 1 is shown in its extreme left hand position. It is connected with the switch points so that as the switch point moves from one position to the other contact is made selectively with either brush 92 or brush 94. A conducting block 100 is carried by the plunger 12 so that in the extreme positions of the solenoid it 75 bridges contacts in series with the segment 96. By the aforementioned connections it is insured that the yellow or green lamps will not be lighted unless the switch points and the plunger 12 are in their extreme proper 80 positions. If they are otherwise, the red lamp R is lighted.

A further safety device is illustrated in connection with the cross-over located at the position of the wire 8. It is possible that a car moving in the direction of the arrow might proceed along line 2 so as to make successive contacts at 32 and 60 without, however, passing the switch point 10. It might then move backwards across the connection 8 upon the line 6 so as to proceed in the opposite direction. In such case the relay 18 would have been de-energized and contacts 20 and 30 opened so that any succeeding car could not operate the system. It is therefore necessary that some means should be provided to cause a clearing of the system during the passage of the car along the cross-over. A contact 100 is provided for this purpose, being connected with the other clearing 90 contacts 76 and 86. On the other hand, the presence of the contact 100 alone might be dangerous by reason of the fact that a car coming from the line 6 along the cross-over 95 8 to the line 2 might make contacts at 32 and 100 60 after clearing the system by making the contact at 100, thereby splitting the switch under a car at the switching point 10. In order to prevent this, a second contact 102 is provided closely adjacent to contact 100 105 but insulated therefrom. If a car proceeds from line 2 to line 6, contact will be made at 100 but the contact 102 will be rendered inoperative by reason of the fact that the contact 104 is broken by the energization of 110 relay 80. On the other hand, current through contact 102 will pass through the closed contact 110 and thereby maintain the relay 80 115 energized. However, if a car is proceeding from line 6 to line 2, contact at 102 will be 120 first made. Since contact 104 is now closed, relay 106 will be energized, breaking the contact 78 and making contact at 108. If the contact 100 is thereafter made, a period 125 will occur when both contacts 102 and 100 130

are simultaneously made, since, although insulated from each other, they are close together. At this time the current through contact 100 will pass not through contact 78 but through contact 108, serving to maintain the relay 106 energized even though the contact 102 will be broken and 100 only remains made. It is not until the car passes beyond contact 100 that the relay 106 is de-energized and contact can be made at 78. It thus happens that the relay 18 is not energized upon such movement of a car.

Referring now to Fig. 2, there is illustrated a similar system in which, however, the control is effected by the passage of the car over insulated sections of the tracks. The overhead line does not enter into this operation, although it is indicated at L as a source of power for the system. Instead of this source of power, it will be obvious that in the case of a steam railroad, for example, any other source of power may be used. In this case, to avoid the necessity of providing excessive electrical current to throw the switch, it will be clear that the solenoids 14 and 16 may merely control a valve or relay or the like so that the switch may be actuated by compressed air or an electric motor driven from an auxiliary supply.

In Fig. 2, 120 indicates the main continuous grounded rail. The other rail includes the insulated segments 122 and 124, the latter continued along the corresponding branch rail 125, as indicated, insulation being provided between the segments and also in the rod connecting the switch points, as indicated at i.

The secondary of a transformer 126 is connected between the section 122 and the main rail 120. The secondary of another transformer 128 is connected between the section 124 and the main rail 120.

If no car is present on the section 122, the relay 130 is energized, maintaining broken the contact at 132, which corresponds to the contact at 36 in the modification of Fig. 1. On the other hand, as soon as a car passes upon this section of the rail, the secondary of the transformer is short-circuited, de-energizing the rail 130 and making contact 132. Thereafter there ensues the same series of operations as occurs upon the making of contact 36. In Fig. 2 the parts which are the same as in Fig. 1 have been so designated, so that the operation may be readily followed.

Depending on whether he intends to proceed straight ahead or on the branch track, the operator regulates the speed of the car so as to enter upon the section 124 when either the green or the yellow lamp is lighted. If he proceeds when the green lamp is lighted, a contact is made at 28. On the other hand, if he proceeds when the red lamp is lighted, the contact is made at 84.

As soon as the section 124 is reached the secondary of transformer 125 is short-circuited, de-energizing the relay 134 which has heretofore held closed contact 136 corresponding to contact 20 and serving to maintain energized the relay 18. When the contact 136 is broken by the release of the armature, the contact 138 is closed. This contact corresponds to the contact made at 60, serving to close the line through either of the solenoids 14 or 16, depending upon the actuation of the relay 82. In this case, also, the relay 18 is of a slow release type so that breaking of contact 30 does not occur until after the switch is thrown. Inasmuch as all of the parts function identically, as heretofore described in connection with the modification of Fig. 1, the description will not be repeated. As soon as the car passes beyond the section 124 of the rails, which section, it will be noted, extends into the branch track beyond the switch, the relay 134 is re-energized, closing contact 136 and re-energizing relay 18, thereby maintaining closed the contact 30.

It will be obvious that the details of the selecting and switch operating circuits may be modified without departing from the invention, the details shown being of preferred and satisfactory embodiments thereof.

One modification of the invention, which in some instances would be quite satisfactory depending upon the character of the traffic, would involve a continuous operation of motor 42 with the elimination of the preliminary controlling means including relays 38 and their associated parts. In this modification, in both the wire or rail systems, the lamps G and Y would be alternately illuminated, the relay 82 being energized during the period of illumination of lamp Y. It would then be necessary for the operator of a car to pass contact 60 or pass over rail 124 during the illumination of the proper lamp although he cannot control the time of its period of illumination.

While the invention has been described in connection with a railroad, it is obviously applicable to the control of vehicular traffic on highways the controlling contacts 32 and 60, or only contact 60, for example, being replaced by pedals or other devices sensitive to the passage of vehicles and the switch being replaced by traffic control lamps. By such device, a driver of a vehicle could be assured of the maintenance of a given light during his passage across an intersection or during the making of a left turn thereat. The signals could be cleared by the use of pedals beyond the intersection corresponding to 76 and 86.

While only two branch roads are shown as diverging from the junction point, it will be clear that more than two may so diverge, the selective passage along any one being con-

trolled by passage of the contact 60, for example, during the corresponding one of several periods corresponding in number to the branches.

5 It will be obvious that numerous other modifications may be made within the scope of the invention as defined by the following claims.

What I claim and desire to protect by Letters Patent is:

10 1. In combination with a road system including a road forming an approach to a junction and branch roads extending from said junction, controlling means for traffic including means for determining the branch road which may be taken by a vehicle from the junction, and means for selectively operating the determining means, said operating means being controlled by the passage of a vehicle into a given portion of the approach road at any instant of one predetermined period of substantial duration to operate the determining means to permit passage upon one branch road, and by the passage of a vehicle into the same portion of the approach road at any instant of another predetermined period of substantial duration to operate the determining means to permit passage upon another branch road.

20 2. In combination with a road system including a road forming an approach to a junction and branch roads extending from said junction, controlling means for traffic including means for determining the branch road which may be taken by a vehicle from the junction, and means for selectively operating the determining means, said operating means being controlled by the passage of a vehicle into a given portion of the approach road at any instant of one predetermined period of substantial duration to operate the determining means to permit passage upon one branch road, and by the passage of a vehicle into the same portion of the approach road at any instant of another predetermined period of substantial duration to operate the determining means to permit passage upon another branch road, the times of said periods being determined by the passage of the vehicle through a portion of the approach road in advance of the said given portion thereof.

30 3. In combination with a road system including a road forming an approach to a junction and branch roads extending from said junction, controlling means for traffic including means for determining the branch road which may be taken by a vehicle from the junction, means for selectively operating the determining means, said operating means being controlled by the passage of a vehicle through a given portion of the approach road during one predetermined period to operate the determining means to permit passage upon one branch road, and by the passage of a vehicle through the same portion of

the approach road during another predetermined period to operate the determining means to permit passage upon another branch road, and means operated by the passage of a vehicle beyond the junction to clear the controlling means for operation by a succeeding vehicle.

4. In combination with a road system including a road forming an approach to a junction and branch roads extending from said junction, controlling means for traffic including means for determining the branch road which may be taken by a vehicle from the junction, means for selectively operating the determining means, said operating means being controlled by the passage of a vehicle through a given portion of the approach road during one predetermined period to operate the determining means to permit passage upon one branch road, and by the passage of a vehicle through the same portion of the approach road during another predetermined period to operate the determining means to permit passage upon another branch road, the times of said periods being determined by the passage of the vehicle through a portion of the approach road in advance of the said given portion thereof, and means operated by the passage of a vehicle beyond the junction to clear the controlling means for operation by a succeeding vehicle.

5. In combination with a railway system including a railway forming an approach to a junction, and branch railways extending from said junction, controlling means for traffic including switch means for determining the branch railway which may be taken by a vehicle from the junction, and means for selectively operating the switch means, said operating means being controlled by the passage of a vehicle into a given portion of the approach railway at any instant of one predetermined period of substantial duration to operate the switch means to permit passage upon one branch railway, and by the passage of a vehicle into the same portion of the approach railway at any instant of another predetermined period of substantial duration to operate the switch means to permit passage upon another branch railway.

6. In combination with a railway system including a railway forming an approach to a junction, and branch railways extending from said junction, controlling means for traffic including switch means for determining the branch railway which may be taken by a vehicle from the junction, and means for selectively operating the switch means, said operating means being controlled by the passage of a vehicle into a given portion of the approach railway at any instant of one predetermined period of substantial duration to operate the switch means to permit passage upon one branch railway, and by the passage of a vehicle into the same portion of the ap-

proach railway at any instant of another predetermined period of substantial duration to operate the switch means to permit passage upon another branch railway, the times of said periods being determined by the passage of the vehicle through a portion of the approach railway in advance of the said given portion thereof.

7. In combination with a railway system including a railway forming an approach to a junction, and branch railways extending from said junction, controlling means for traffic including switch means for determining the branch railway which may be taken by a vehicle from the junction, and means for selectively operating the switch means, said operating means being controlled by the passage of a vehicle through a given portion of the approach railway during one predetermined period to operate the switch means to permit passage upon one branch railway, and by the passage of a vehicle through the same portion of the approach railway during another predetermined period to operate the switch means to permit passage upon another branch railway, and means operated by the passage of a vehicle beyond the junction to clear the controlling means for operation by a succeeding vehicle.

8. In combination with a railway system including a railway forming an approach to a junction, and branch railways extending from said junction, controlling means for traffic including switch means for determining the branch railway which may be taken by a vehicle from the junction, and means for selectively operating the switch means, said operating means being controlled by the passage of a vehicle through a given portion of the approach railway during one predetermined period to operate the switch means to permit passage upon one branch railway, and by the passage of a vehicle through the same portion of the approach railway during another predetermined period to operate the switch means to permit passage upon another branch railway, the times of said periods being determined by the passage of the vehicle through a portion of the approach railway in advance of the said given portion thereof, and means operated by the passage of a vehicle beyond the junction to clear the controlling means for operation by a succeeding vehicle.

9. In combination with a road system including a road forming an approach to a junction and branch roads extending from said junction, controlling means for traffic including means for determining the branch road which may be taken by a vehicle from the junction, and means for selectively operating the determining means, said operating means being controlled by the passage of a vehicle into a given portion of the approach road at any instant of one predetermined

period of substantial duration to operate the determining means to permit passage upon one branch road, and by the passage of a vehicle into the same portion of the approach road at any instant of another predetermined period of substantial duration to operate the determining means to permit passage upon another branch road, said operating means including a selective circuit controlling device for determining the periods.

10. In combination with a road system including a road forming an approach to a junction and branch roads extending from said junction, controlling means for traffic including means for determining the branch road which may be taken by a vehicle from the junction, and means for selectively operating the determining means, said operating means being controlled by the passage of a vehicle into a given portion of the approach road at any instant of one predetermined period of substantial duration to operate the determining means to permit passage upon one branch road, and by the passage of a vehicle into the same portion of the approach road at any instant of another predetermined period of substantial duration to operate the determining means to permit passage upon another branch road, said operating means including a selective circuit controlling device for determining the periods set into operation by the passage of the vehicle through a portion of the approach road in advance of the said given portion thereof.

11. In combination with a railway system including a railway forming an approach to a junction, and branch railways extending from said junction, controlling means for traffic including switch means for determining the branch railway which may be taken by a vehicle from the junction, and means for selectively operating the switch means, said operating means being controlled by the passage of a vehicle into a given portion of the approach railway at any instant of one predetermined period of substantial duration to operate the switch means to permit passage upon one branch railway, and by the passage of a vehicle into the same portion of the approach railway at any instant of another predetermined period of substantial duration to operate the switch means to permit passage upon another branch railway, said operating means including a selective circuit controlling device for determining the periods.

12. In combination with a railway system including a railway forming an approach to a junction, and branch railways extending from said junction, controlling means for traffic including switch means for determining the branch railway which may be taken by a vehicle from the junction, and means for selectively operating the switch means, said operating means being controlled by the passage of a vehicle into a given portion of the approach

- approach railway at any instant of one predetermined period of substantial duration to operate the switch means to permit passage upon one branch railway, and by the passage 5 of a vehicle into the same portion of the approach railway at any instant of another predetermined period of substantial duration to operate the switch means to permit passage upon another branch railway, said operating 10 means including a selective circuit controlling device for determining the periods set into operation by the passage of the vehicle through a portion of the approach railway in advance of the said given portion thereof. 15 13. In combination with a railway system including a railway forming an approach to a junction, and branch railways extending from said junction, controlling means for traffic including switch means for determining the branch railway which may be taken by a vehicle from the junction, and means for selectively operating the switch means, said operating means being controlled by the passage of a vehicle through a given portion of the approach railway during one predetermined period to operate the switch means to permit passage upon one branch railway, and by the passage of a vehicle through the same portion 25 of the approach railway during another predetermined period to operate the switch means to permit passage upon another branch railway, the control of said operating means taking place irrespective of whether driving power is or is not being supplied to the vehicle during passage through the given portion of the approach railway. 30 14. In combination with a railway system including a railway forming an approach to a junction, and branch railway extending from said junction, controlling means for traffic including switch means for determining the branch railway which may be taken by a vehicle from the junction, and means for selectively operating the switch means, said operating means being controlled by the passage of a vehicle through a given portion of the approach railway during one predetermined period to operate the switch means to permit passage upon one branch railway, and by the passage of a vehicle through the same portion of the approach railway during another predetermined period to operate the switch means to permit passage upon another branch railway, the control of said operating means taking place irrespective of whether driving power is or is not being supplied to the vehicle during passage through the given portion of the approach railway. 35 15. In combination with a railway system including a railway forming an approach to a junction, and branch railways, extending from said junction, controlling means for traffic including switch means for determining the branch railway which may be taken by a vehicle from the junction, and means for selectively operating the switch means, said operating means being controlled by the passage of a vehicle through a given portion of the approach railway during one predetermined period to operate the switch means to permit passage upon one branch railway, and by the passage of a vehicle through the same portion of the approach railway during another predetermined period to operate the switch means to permit passage upon another branch railway, the control of said operating means being effected by the electrical connection of parts of the rails forming said railway through the vehicle. 40 16. In combination with a railway system including a railway forming an approach to a junction, and branch railways extending from said junction, controlling means for traffic including switch means for determining the branch railway which may be taken by a vehicle from the junction, means for selectively operating the switch means, said operating means being controlled by the passage of a vehicle through a given portion of the approach railway during one predetermined period to operate the switch means to permit passage upon one branch railway, and by the passage of a vehicle through the same portion of the approach railway during another predetermined period to operate the switch means to permit passage upon another branch railway, the times of said periods being determined by the passage of the vehicle through a portion of the approach railway in advance of the said given portion thereof, and the control of said operating means taking place irrespective of whether driving power is or is not being supplied to the vehicle during passage through the given portion of the approach railway. 45 17. In combination with a railway system including a railway forming an approach to a junction, and branch railways extending from said junction, controlling means for traffic including switch means for determining the branch railway which may be taken by a vehicle from the junction, means for selectively operating the switch means, said operating means being controlled by the passage of a vehicle through a given portion of the approach railway during one predetermined period to operate the switch means to permit passage upon one branch railway, and by the passage of a vehicle through the same portion of the approach railway during another predetermined period to operate the switch means to permit passage upon another branch railway, and signalling devices for indicating the duration of the predetermined periods to the operator of the vehicle. 50 18. In combination with a railway system including a railway forming an approach to a junction, and branch railways, extending from said junction, controlling means for traffic including switch means for determining the branch railway which may be taken by a vehicle from the junction, and means for selectively operating the switch means, 55

a junction, and branch railways extending from said junction, controlling means for traffic including switch means for determining the branch railway which may be taken by a vehicle from the junction, means for selectively operating the switch means, said operating means being controlled by the passage of a vehicle through a given portion of the approach railway during one predetermined period to operate the switch means to permit passage upon one branch railway, and by the passage of a vehicle through the same portion of the approach railway during another predetermined period to operate the switch means to permit passage upon another branch railway, signalling devices for indicating the duration of the predetermined periods to the operator of the vehicle, and other signalling devices for indicating to said operator the condition of the switch means.

In testimony of which invention, I have hereunto set my hand, at Philadelphia, Pennsylvania, on this 11th day of August, 1930.

ARCHIBALD H. KINGHORN, JR.
